Primary Examiner — Erich G Herbermann*Assistant Examiner* — Rene H. Kadoo(74) *Attorney, Agent, or Firm* — Weitzman Law Offices, LLC(57) **CLAIM**

The ornamental design for a wallet card, as shown.

DESCRIPTION

FIG. 1 shows a top perspective view of the wallet card. FIG. 2 shows a front elevation view thereof.

FIG. 3 shows a rear elevation view thereof.

FIG. 4 shows a left elevation view thereof.

FIG. 5 shows a right elevation view thereof.

FIG. 6 shows a top plan view thereof; and,

FIG. 7 shows a bottom plan view thereof.

The dot-dash broken line(s) define the bounds of the claimed design and form no part thereof.

The broken lines in the drawings represent(s) portions of the wallet card, and form no part of the claimed design.

1 Claim, 3 Drawing Sheets
